GAME BOARD

Charlemagne Tower IV, 217 E. 60th St., New York, N.Y.

Filed July 28, 1960, Ser. No. 61,563

Term of patent 14 years

(Cl. D34—5)

The single figure is a perspective view of a game board embodying my new design.

The back of the game board is plain, and the side opposite to that disclosed in the drawing has the same appearance as the side disclosed.

I claim:

The ornamental design for a game board, as shown and described.
